CLAIM

I claim the ornamental design for an air purifier enclosure, as shown and described.

DESCRIPTION

FIG. 1 is a front elevation view of the air purifier enclosure; FIG. 2 is a rear elevation view thereof; FIG. 3 is a left side elevation view thereof; FIG. 4 is a right side elevation view thereof; FIG. 5 is an enlarged top plan view of thereof; FIG. 6 is an enlarged bottom plan view of thereof; FIG. 7 is a front perspective view thereof; and, FIG. 8 is a rear perspective view thereof.

The broken lines in the drawings are for purposes of illustrating optional features such as wheels, a logo, an example of a type of control panel, and form no part of the claimed design.
